UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER FOR SUBMARINE HAMMER DRILLS.

Application filed June 29, 1926. Serial No. 119,425.

This invention relates to submarine hammer drills, in which a fluid operated rock drill of the hammer type is adapted to be lowered and submerged for submarine drilling, as disclosed in my copending application, Serial No. 52,136, filed August 24, 1925, now Patent 1,610,372.

The present invention is concerned with the drill steel holder or retainer for retaining the drill steel in the drill and the objects of the invention are to secure an efficient steel holder within the bell or exhaust chamber of the drill, which will not work loose and release the steel during drilling operations and is conveniently and readily adjusted from the drill barge or from any convenient point at the surface.

A preferred form of the invention is shown in the drawings, in which

20 Figure 1 is a side elevation of so much of a submarine hammer drilling element or drilling frame as will serve to illustrate the invention.

Figure 2 is an enlarged detail sectional elevation of a portion of the front head of the drill and the bell or exhaust chamber showing the steel holder clamps or jaws closed around a collared steel,

30 Figure 3 is a fragmentary detail sectional view showing the jaws open,

Figure 4 is a detail view similar to Figure 2 showing a modification in which a lugged steel is used, and

35 Figure 5 is a detail horizontal sectional view of Figure 4 taken on the line 5—5 looking upwardly in the direction of the arrows.

Referring to the drawings, a portion of the drilling element or drilling frame A is shown in Figure 1 and this drilling frame carries the fluid actuated hammer drill B having the cylinder C, front head D and bell or exhaust chamber E. The hammer drill may be mounted on the drilling frame 45 in any suitable manner, in this instance being shown mounted by means of the plates or bracing members F and G. It is to be understood that in the operation of drilling, the entire drilling frame or rock drill is lowered into the water as disclosed and described in detail in my aforesaid copending application. Pressure fluid is supplied for the operation of the rock drill through the pipe H and cleansing water for the hollow

drill steel J or K is supplied through the pipe L.

In Figure 2 a collared steel is shown with an appropriate chuck therefor and in Figure 4 a lugged steel is shown with an appropriate chuck. In both instances the rock 60 drills are shown provided with anvil blocks O for purposes of illustration and the exhaust from the rock drill passes through the exhaust passage P into the bell E or exhaust chamber which prevents the water 65 from entering the rock drill itself. Rotation is applied to the drill steel by suitable means, in this instance the chuck in Figure 2 being provided with the gear Q meshing with the pinion R on the vertical shaft 70 S which is guided in the bearing T and extends to the surface or to the upper portion 75 of the drilling element and is adapted to be rotated by independent motor (not shown). In Figure 4 the gear U in the chuck meshes with the pinion R of the shaft S. Since the particular construction of the chucks shown in Figures 2 and 4 form no part of the present invention, they need not be further described.

Within the bell E are pivoted two similar clamps or jaws a, which are adapted to close around the drill steel preferably by their own weight, and may be opened or rocked backwardly on their pivots by suitable 85 means extending outside the bell and having operative connections extending to the surface or to a convenient point for manual manipulation. In this instance the pivot pins b are in the form of bolts having the heads c and squared shanks which pass through the squared socket portions e of the jaws. Bushings f are preferably provided in the seats formed in the walls of the bell and arms g are held on the pivot pins outside the shell by means of the nuts h. The arms g extend toward each other and their inner ends are connected by the rods j to the point k preferably at the central portion 90 of the lever o pivoted at the point p above the arms g to a convenient point on the frame. The outer end q of the lever o may be connected to the rope or cable r which extends to the surface or to a convenient point 95 for hand manipulation.

100 In the operation of the apparatus, the lever o is pulled upwardly or backwardly to enable the drill steel J or K to be inserted in

the chuck. By loosening the lever *o* the weight of the clamps is sufficient to cause them to close above the shank of the steel so that the collar *s* on the drill steel shown in Figure 2 cannot pass beyond the clamps. In the construction shown in Figure 4 double clamping or retaining means are provided because the lugs *t* of the steel are held within the chuck as well as being prevented from passing beyond the clamps. The drilling element of the rock drill may be raised from the water leaving the steel in the hole by loosening the clamps and the rock drill may be located upon the steel and clamped thereto again by proper manipulation of the clamps.

I claim:

1. In a submarine hammer drill, the combination of a front head and bell, and a drill steel retainer comprising upwardly opening retaining jaws pivotally mounted within the bell and adapted to clamp and release a drill steel, pivoted arms located side by side outside the bell and extending inwardly toward each other for rocking said jaws upwardly and downwardly about their pivots, and a connection extending from said arms to the surface for operating said arms, said connection being adapted to be pulled upwardly for disengaging the jaws and released for clamping the jaws.

2. In a submarine hammer drill, the combination of a front head and bell, and a

drill steel retainer comprising upwardly and downwardly swinging retaining jaws pivotally mounted within the bell and adapted to clamp and release a drill steel, pivoted arms located at one side externally to the bell and having their free ends extending inwardly toward each other for rocking said jaws about their pivots, a pivoted lever, rods connecting the lever and the said arms, and operating means connected to the lever and extending to the surface for manual manipulation.

3. In a submarine hammer drill, the combination of a front head and bell, and a drill steel retainer comprising upwardly opening and downwardly closing retaining jaws pivotally mounted within the bell and adapted to clamp and release a drill steel, pivoted arms located outside the bell and having their free ends extending inwardly toward each other for rocking said jaws about their pivots, a lever pivotally mounted at one end above the said arms, rods connecting the inner free ends of said arms to the central portion of the lever, and a connection extending from the outer free end of said lever to the surface for opening said jaws by lifting the lever, and permitting the jaws to close upon lowering the lever.

In testimony whereof I have signed this specification.

CHARLES C. HANSEN.
